[57] CLAIM

The ornamental design for a pendant or the like, substantially as shown and described.

DESCRIPTION

FIG. 1 is a perspective view of a pendant or the like showing my new design;

FIG. 2 is a front elevational view thereof;

FIG. 3 is a top plan view thereof;

FIG. 4 is a left side elevational view thereof; and a rear elevational view is a mirror image of FIG. 2.
